UNITED STATES PATENT OFFICE.

HERMANN DONNER, OF CHEMNITZ, GERMANY.

KNITTING-MACHINE.

SPECIFICATION forming part of Letters Patent No. 650,376; dated May 29, 1900.

Application filed July 10, 1899. Serial No. 723,402. (No model.)

To all whom it may concern:

Be it known that I, HERMANN DONNER, a subject of the King of Saxony, and a resident of Chemnitz, in the Kingdom of Saxony, German Empire, have invented a new and Improved Automatic Straight-Knitting Machine, (System, Lamb,) of which the following is a full and exact specification.

This invention is designed to admit by means of a new combination of mechanism in a "Lamb" straight-knitting machine for the entirely-automatic production of a sock or stocking, the characteristics of such stockings being their seamlessness and perfect shape obtained by combining therein the so-called "Griswold" heel (bag-like ware) with the regularly-narrowed toe and instep in front of the heel and calf.

My invention is calculated to admit of the entirely-automatic production of full-fashioned stockings in an uninterrupted sequence of different operations. The process of forming the so-called "Griswold" heel by rendering certain needles idle and active by lowering and raising their feet at predetermined intervals is known from United States Letters Patent No. 557,641, of 1896, to Benner, and English Patent No. 13,126 of 1891 to Rowlett, and that of regularly narrowing and widening by transferring meshes to adjacent needles with the aid of points is also known from United States Letters Patent No. 391,011 to Bejér, transferred to me; but never before have these two methods for imparting a desired shape to knitted fabric been executed automatically and conjointly in one machine and in such a manner that the mechanism employed for disengaging and engaging mesh-holding working needles during the formation of the heel can be used in combination with the automatic narrowing apparatus for knitting a toe thoroughly narrowed down to the last mesh. In the case of widening by transferring stitches to empty needles the same mechanism serves to render such needles active one after the other, as required, by raising their feet out of the needle-bed into the path of the knitting-cams.

The present invention, briefly stated, comprehends, first, a construction of a new automatic straight-knitting machine (system, Lamb) combining the two methods of narrow-

ing and widening by rendering idle or active certain needles by plunging their feet and by transferring stitches to adjacent needles with the aid of points; secondly, means for allowing the fabric—as, for instance, in the case of a toe—to be narrowed down to the last mesh, and, finally, it comprehends various minor features of construction whereby advantages are gained, all of which will be hereinafter particularly described.

In order to make my invention more clear, I refer to the accompanying drawings, forming part of this specification, and in which—

Figure 1 represents a plain seamless sock with ribbed top and the so-called "Griswold" heel and regularly-narrowed toe. Fig. 2 shows the same sock with ribbed leg and shaped instep. Fig. 3 shows a plain seamless sock, as per Fig. 1, but with shaped instep. Fig. 4 represents a full-fashioned seamless stocking with the so-called "Griswold" heel and regularly-narrowed toe and calf, the narrowings of the leg for forming the calf being effected at both sides of the same. Fig. 5 shows a similar stocking with shaped leg and instep, the leg being ribbed, the narrowings of the leg in this case running down at the back in the center of the calf. Fig. 6 represents a fully-fashioned seamless stocking with the so-called "Griswold" heel and regularly-narrowed toe, instep, and leg, the narrowings of the leg running down at the back in the center of the calf. Fig. 7 represents a side elevation of the machine, showing four heads. Fig. 8 is a section on line A B, Fig. 7, some accessory parts being omitted for more clearly illustrating the most important parts of the machine. Fig. 9 is a left-hand end elevation of said machine on Fig. 7, yarn-stand and weight-relieving device being not shown. Fig. 10 shows in a cross-section on line C D of Fig. 7 the relation of pattern-chain to the eccentrics x' to x^7 . Fig. 10^a is a view of one set of coacting eccentrics $c' c^2 c^3$, forming one such set, one of the disks being in section and partly cut off. Fig. 11 is a plan view of an eccentric y^4 in conjunction with one of the cam-displacing bars v' to v^7 . Fig. 11^a is a cross-section thereof as on the line E F of Fig. 11. Fig. 12 is a side view of the eccentric y^7 at the commencement of its run, relieving the pulling-off weight during

formation of the heel. Fig. 12^a is a section thereof as on the line G H of Fig. 12. Fig. 12^b is a side view of said eccentric during its run. Fig. 12^c is a section thereof as on the line I K of Fig. 12^b. Fig. 13 is a plan view of the pattern-chain and intermediate mechanisms for reciprocating eccentrics x^1 to x^7 . Figs. 14 to 20 show in transverse vertical sections through the needle-beds and needle-operating bars, point-carriers and followers being represented in side view, the empty needles being thrown inactive by having their feet plunged into the needle-bed. Fig. 21 is a transverse section through a needle-bed with jacks and needles in connection with follower and reciprocating mechanism as on line R S of Fig. 28^a. Fig. 22 is a plan view thereof. Fig. 23 shows in a vertical section through a needle-bed the carriage guide-bars and cam-regulating bars, the segment mechanism for raising needles in receiving position thrown out of action. Fig. 24 is a section through a spring-controlled pin carrying needle-operating segment and eccentric projection. Fig. 25 is a plan view of the needle-operating segment mechanism, with its reciprocating bars. Fig. 26 is a plan view of one of the spring-actuated segments, with eccentric projection in conjunction with its displacing-bar. Fig. 27 is a vertical section through a needle-bed, the carriage guide-bars, and cam-regulating bars, the segment mechanism for raising needles into receiving position thrown into action. Fig. 28 is a plan view of a needle-bed, with its needles, showing the knitting-cams in relation with auxiliary triangle e^0 . Fig. 29 shows in side view the end step c^0 in relation to the abutment-bar, throwing into and out of action the segment mechanism for raising the needles into receiving position. Fig. 30 is a plan view of the cam-carriage and the bars for reciprocating the segment mechanism and the knitting-cams. Fig. 26^a is an end elevation of the mechanisms actuating point-carriers and followers seen from left-hand side of Fig. 7. Fig. 27^a is a cross-section on the line N O of Fig. 26^a, showing the regulating-screw, with its sliding block and adjuncts. Fig. 28^a is a partial top view of the machine, taken from the right-hand side of Fig. 7. Fig. 29^a is a transverse vertical section through the needle-beds seen as on the line P Q of Fig. 28^a, showing the active and inactive positions of needles during the formation of the so-called "Griswold" heel and the idle positions of the needle-operating bars and point-carriers of the narrowing apparatus. Fig. 30^a is a transverse vertical section through the machine, as on the line R S of Fig. 7, representing the automatic weight-relieving tackle. Fig. 31 is the right-hand end elevation of the machine, as per Fig. 7, showing the coupling engaging with the yoke of the cam-carriage. Fig. 32^a is a partial side elevation thereof. Fig. 32^a is a section through the coupling in direction of T U of Fig. 32. Fig. 33 is a plan view

showing the disengaging fork n^0 n^0 thrown out of gear; Fig. 34, the same, but thrown into gear. Fig. 35 is an elevation of the wheels reciprocating the cam-shaft appertaining to the narrowing apparatus. Fig. 36 is an end elevation thereof. Fig. 37 is a cross-section of the needle-bed, needle and needle-controlling jack being in side view. Fig. 38 is a section of the solid foundation-plate of the needle-bed, showing in side view transverse groove for division-plate and longitudinal recess n^3 . Fig. 39 is a plan view of a needle-bed holding separate division-plates. Fig. 40 is a cross-section of the knocking-over comb of the needle-bed. Fig. 41 is a plan view of one of the longitudinal toothed cross-plates securing the transverse division-plates against displacement. Fig. 42 is a side view of a division-plate. Fig. 43 is a side view of a needle-controlling jack, with its basal claw-shaped projection n^0 .

Referring to the drawings, A represents a framework of appropriate form to support the various parts of the machine. Upon this frame are fixed the oppositely-inclined needle-beds B B, the needles of which are reciprocated to effect tubular and other knitting by means of the knitting-cams traveling thereon. These cams are supported on carriages b, sliding between grooved bars b^2 b^3 , Fig. 8, and connected through rods b' , Figs. 7, 32, and 32^a, by yoke n^2 , which in turn is reciprocated in the manner as hereinafter described. Mounted transversely in the machine and extending through the frame at either end is the main driving-shaft d, Figs. 7 and 8, carrying loosely on one end the fly-wheel r^8 , with the pulley firmly attached to it, and on the opposite end fastened upon said shaft a beveled wheel r^{12} , gearing with a corresponding one r^{13} upon the hand-wheel shaft d'. Interposed between fly-wheel r^8 and framing A and fixed upon shaft d is cog-wheel r, which engages with crank-wheel r' on shaft d², disposed transversely in the two sides of the frame and connected by rod h, Figs. 7 and 32, with pivoted lever g, which again is connected with yoke n^2 by link n'. Shaft d², Fig. 8, further carries beveled wheel r^2 , gearing with beveled pinion r^3 . Fixed concentrically upon the same axis as r^3 is spur-wheel r^{10} , which is destined to rotate the cam-shaft i, longitudinally mounted in the framework A, by being thrown into gear with spur-wheel r^9 , fixed on shaft i. From axis d³ is also derived the rotary motion of cam-shaft e by cog-wheel r^4 engaging with the intermediary wheel r^5 , which rotates wheels r^6 and r^7 , the latter being fastened upon cam-shaft e, which is, like shaft i, longitudinally arranged in the frame.

To impart rotary motion to the main driving-shaft d, thus actuating the depending mechanism, the following arrangement is made: Parallel to and close beneath hand-wheel shaft d' is disposed a longitudinal shaft w², with a certain number of hand-levers

firmly secured upon it. The end lever h^0 , Fig. 8, is provided with a projecting arm b^4 , the extremity of which, being slotted, straddles a pin s^{11} , let into bar s , arranged vertically movable on the side of the frame. Bar s has at its upper end an offset or recess j^0 , into which extends the spring-controlled rod s' , that forms the connection with the boss of cone o , which is disposed longitudinally movable upon shaft d , but is prevented from turning independently of the latter by a spline fixed therein and fitted loosely into a corresponding internal slot in the boss of cone o . Said cone o works in a corresponding cavity 15 of the fly-wheel pulley r^8 and impels, when steadily pressed into said cavity, shaft d to rotate in the same direction as fly-wheel r^8 . To press cone o into the cavity of said pulley, lever h^0 has to be raised into the position as 20 shown in dotted lines, Fig. 8. Bar s is pushed downward, whereby rod s' is pressed into the direction of the arrow, Fig. 8, by offset j^0 acting upon the extremity of rod s' , and thus cone o is pressed into its cavity, shaft d is 25 forcibly rotated, thereby rotating crank-wheel r' , pinion r^3 , cam-shafts i and e , and hand-wheel shaft d' . The relative sizes of the different wheels is arranged in such a manner that one revolution of cam-shaft e is equal to 30 one revolution of crank-wheel shaft d' or one movement to and fro on the needle-beds B of the cam-carriage b . Between the two standards on the right-hand side of the machine is arranged the well-known pattern-chain device, Figs. 7 and 8. It consists of a ratchet-wheel m^2 , securely fastened upon a pin m^3 , a sprocket-wheel m^4 , fixed upon the same axis as the ratchet-wheel, and the endless chain m , with its studs n , passing around the wheel m^4 . 35 The pattern-chain device receives its intermittent step-by-step motion by cam-shaft e , which for this purpose carries disk y . This disk, rotating with shaft e , is provided with a semicircular incision which actuates pawl 40 supporting lever h' (bearing upon said disk) in such a manner that pawl h' with every revolution of shaft e moves ratchet-wheel m^2 one tooth, and consequently sprocket-wheel m^4 , which latter moves pattern-chain forward by 45 one bar or link. A notched disk m^5 , firmly secured to pin m^3 by the side of sprocket-wheel m^4 , is designed by means of spring m^6 entering the notches to regulate and steady the step-by-step motion of said wheel and prevent 50 it from racking the pattern-chain more than one link or bar at the time. The manner in which the studs n upon pattern-chain m control the operation of the knitting and other mechanisms will be more fully described hereinafter.

C C in Fig. 7 represent the slide-bars destined to support the automatic pulling-off apparatus, the construction and operation of which are known from my Patent No. 629,892, patented August 1, 1899. The operation and construction of the automatic narrowing device are likewise known from United States

Letters Patent No. 391,011 to Beyér, transferred to me. The arms h^{19} h^{20} , Fig. 8, supporting the longitudinally-movable bars that hold point-carriers b^0 , as well as the arms l^6 l^7 , Fig. 9, supporting the grooved needle-operating bars l^6 l^7 , are fulcrumed on longitudinal rock-shafts d^4 d^5 , the depending arms being reciprocated by eccentrics upon cam-shaft i .

I refrain from giving a detailed description of the automatic narrowing device in this specification. I shall only mention it incidentally and in so far as it has been improved in my present invention.

Hitherto in making entirely-seamless fashioned socks or stockings in automatic straight-knitting machines (system, Lamb) the work is usually commenced at the toe part of the foot. The toe is formed either by rendering certain needles idle and active (Bennor) or by widening, as described in English Patent No. 13,126 (Rowlett) of 1891, whereupon the formation of the plain portion of the foot is continued in the ordinary way by throwing the cams into the tube-knitting positions. Afterward the heel is made by working backward and forward upon one needle-bed only and with a number of needles varying successively, so as to produce a bag-like shape, what in the art is known as "Griswold" heel. Articles made in this way, however, exhibit many imperfections, especially with regard to shape and finishing, which detracts from the marketability of such articles.

To produce a well-proportioned and perfectly-finished sock or stocking, I reverse the order of operations by making the leg portion first and subsequently in making the foot by forming an improved heel of bag form, (Griswold,) an instep close to the heel, and a toe, which latter I fashion by narrowing down to the last needle, as it is done with hand-wrought stockings. For this purpose I construct a needle-bed, as shown in Figs. 37 to 43, with a solid foundation-plate n^2 , provided with a certain number of transverse grooves of the gage desired. In these grooves are mounted parallel to one another plates n^4 , constituting guides for the needles and the needle-controlling jacks a , which are movably arranged between said plates. The bifurcated needle-jacks employed by me in this instance differ from those generally used in so far as they are provided on their bases with a claw-shaped projection n^9 , which serves to fix said jacks when sunk into the needle-bed by entering a corresponding recess n^8 , cut longitudinally into the foundation-plate n^2 of the needle-bed. The knitting-needles, which are fitted to the longitudinal slot of the controlling-jacks, are consequently forced to follow the jacks with the effect that during the formation of the heel the feet of the needles knitting the heel are infallibly either plunged into the needle-bed out of the path of the reciprocating cams or they are raised into the path of the said cams, with the effect that those needles which during narrowing process with the

aid of points were emptied of their stitches are rendered idle by plunging their feet without their heads obstructing the motion of the points.

- 5 The needle-jacks have at their foot end a cam-slot a , through which a rod passes, common to all of them, suitably disposed in the needle-bed, and which rod, coacting with the cam-slots a , determines the position and 10 movement of the jacks in the needle-bed between the division-plates. To lend to the division-plates of the needle-bed an additional support from above, I employ a cross-plate n^0 , provided at its longitudinal sides with square 15 teeth n^6 . This cross-plate is laid into the notch n^5 cut into the top edge of the division-plate n^4 , whereby the teeth n^6 of the cross-plate lie within the spaces formed between the different plates n^4 and secure the same in 20 position, as is illustrated in Fig. 39. To provide a facile replacement of the knocking-over portion of the needle-bed, which in the course of work has to suffer the greatest wear, this part n' consists of a separate piece suitably attached to the solid foundation-plate 25 n^2 . This construction of a needle-bed combines utmost durability with the advantage of permitting such needle-bed to be adapted for the finest-gage machine of the kind, 30 while it renders the machine more efficient and its work more perfect.

As already mentioned, the shank of the knitting-needles is fitted to the longitudinal slot of jack a , by which latter they are held 35 and controlled in such a manner that they may move lengthwise between the division-plates, but never vertically, independent of the jacks. If jack a , Figs. 21 and 22, is brought into position a' , the needle governed 40 or held by said jack must follow its vertical motion, being consequently drawn into the needle-bed. The foot of the needle disappears completely below the surface of the needle-bed in the position shown by f' and 45 can therefore no longer be reciprocated by the knitting-cams. If, on the other hand, jack a is brought back from position a' into position a , then needle-foot f is raised again out of the guideways of the needle-bed into 50 the path of the knitting-cams, and the needle is consequently rendered active. The displacing of jacks a and, corresponding with it, the putting into and out of action of the needles, is effected by followers i i' , Figs. 55 28^a, 21, and 22, by means of shoulders u u^2 , Figs. 21 and 22, impinging against the up-projecting foot extremities of the jacks and by either pulling them downward or pushing them up again into their original position, in 60 the manner as hereinafter more particularly described.

The working of socks or stockings, as illustrated on Sheet 1, either can be commenced by forming the net (Fig. 4 at A a) or by transferring to the needles a rib top (Figs. 1 and 3 at B b) or stocking-leg (Figs. 2, 5, and 6 at C c) by means of my transferring apparatus,

United States Letters Patent No. 527,674, dated October 16, 1894. This done and after mounting a setting-up comb and attaching thereto a pulling-off weight, Fig. 30^a, the machine is set to work, as described, by raising lever h^0 , Fig. 8. The oscillatory stops c c^0 , Fig. 8, disposed in proximity to the needle-beds and projecting into the path of the reciprocating cams, are regulated in such a manner by means of studs upon pattern-chain m , acting upon the intermediate levers and links, that said cams are thrown into the tube-knitting positions—i. e., the set of cams 75 pertaining to the front needle-bed is active while that of the back needle-bed is idle, and vice versa. The machine now knits a straight tubular plain web, the top part of a leg of a stocking, or any other certain and predetermined number of courses regulated by the pattern-chain. After knitting the straight tubular piece the narrowing of the calf portion would have to be effected, carried out on both sides of the leg, as in Fig. 4, and to 80 throw the narrowing mechanism into action, Figs. 10 and 13, a stud n is fixed upon pattern-chain m , which stud raises lever p^0 , Fig. 8, and lever h^2 by means of the connecting-rod t . The wedge-shaped projection u , Figs. 35 and 85 36, upon a rectangular enlargement of the boss of lever h^2 upon shaft i depresses a similar but oppositely-beveled projection upon the spring-controlled clutch v , which is pivoted at q' upon the boss of wheel r^9 within reach of stud q^2 , af 90 fixed to the rotating wheel r^{10} , with the effect that said stud q^2 , bearing against clutch v , moves wheel r^9 a short but sufficient distance to cause the teeth of wheel r^9 to engage with those of wheel r^{10} . Now wheel r^9 , with cam-shaft i , will make one revolution, after which 95 it will stop again, as from that part of wheel r^9 marked j , the teeth have been cut away and as clutch v has resumed its normal position, lever p^0 , Fig. 8, having passed over stud 100 n and having reciprocated the intermediate levers and links accordingly. During this revolution of cam-shaft i , which causes the narrowing operation to take place, carriage b must not move, but must discontinue its 105 course at the end of its stroke. To this end cam y^0 upon cam-shaft i , Figs. 31 and 32, raises pivoted lever g^5 , which by means of connecting-rod t^0 reciprocates lever g^4 in such a manner that wedge l^3 , secured to lever g^4 , is 110 forced between the spring-retracted ends of pivoted fork n^0 , thus causing the closing of the opposite ends of said fork, Figs. 33 and 34. Fork n^0 being closed, or rather the two sides brought parallel to one another, cross-bolt q^0 , 115 Figs. 32^a, 32, 33, and 34, slides upon its tapered ends and lifts spring-impelled pin q^3 out of its recess in the lower portion of the coupling h^0 , Fig. 32^a, thus liberating the latter from the upper coupling n^2 . Now the lower portion 120 alone continues its to-and-fro motion, while the top portion n^2 , which is connected with carriage b , is held fast. After finishing the narrowing operation fork n^0 , Fig. 33, is opened 125 130

again by cam y^0 . Pin q^3 being released catches in the recess in the lower portion of coupling h^0 and establishes again connection between the upper and the lower portions of said coupling, whereupon carriage b resumes its usual to-and-fro motion imparted to n^2 by means of h^0 . The narrowing process itself takes place in a similar manner as described in United States Letters Patent No. 391,011 5 to Beýer, transferred to me, dated October 16, 1888, only that in the present instance the throwing out of action of the needles emptied of their stitches during said process is done in a different and in this combination entirely new way. For this purpose are disposed lengthwise and on both sides of the frame, as shown in Fig. 30^a, rock-shafts d^6 d^7 , upon which are fixed a certain number of arms n^5 n^6 , perforated at their upper end and forming bearings of rods d^8 d^9 . Upon shafts d^6 d^7 are also fixed levers h^8 h^4 , coming into contact with cams y' upon cam-shaft i . The levers h^8 h^4 are held in their positions by suitably-disposed retracting-springs. Followers 10 i' to i^4 , which are supported in their respective positions just above and parallel to the needle-beds by slide-blocks i^5 , are provided at their ends with slotted - up projections, into the slots of which rods d^8 d^9 are fitted, reciprocating said followers, with the effect 15 that the shoulders u' u^2 upon the under side of the followers on the latter being moved outward impinge against the turned-up foot extremities of jacks a and pull them downward, whereby, as shown hereinbefore, the 20 respective needle or needles are thrown out of action, Fig. 19. The followers i' to i^4 are immediately after having pulled down jacks a brought back by the reciprocating mechanism into their original inactive position, 25 Fig. 20. The movement of the followers i' to i^4 in opposite directions across the space of one needle on each side of the needle-bed (see arrow in Fig. 22) has to take place immediately after the needles have been emptied of 30 their stitches during the narrowing process, and it is transmitted by connecting-bars s^3 to s^6 , (see Figs. 21, 26^a, and 28^a.) which are movably fitted in longitudinal supporting-bars 35 i^6 i^7 . For the purpose of reciprocating bars s^3 to s^6 the following arrangement is made: At each end of the machine and parallel to the needle-beds are mounted in fast brackets oppositely-pitched screws i^0 i^{00} , Fig. 7, carrying 40 correspondingly-threaded bosses g' g^2 , which are oppositely displaced every time the screws are actuated. Bosses g' g^2 , Figs. 26^a, 27^a, and 28^a, are provided with rigid arms a^4 , extending on both sides transversely and parallel to 45 the needle-bed. By means of these arms the connecting-bars s^4 s^5 are actuated by screw i^{00} , and s^3 s^6 by screw i^0 , whereas the connecting-bars s^3 to s^6 in turn reciprocate followers i' to i^4 , of which i' is joined to s^3 , i^2 to s^4 , i^3 to s^5 , and i^4 to s^6 . In order to reciprocate 50 screws i^0 i^{00} , a cam on cam-shaft i is brought to bear upon rollers w , Fig. 8, w^0 , Fig. 9, os-

cillating levers h^5 h^6 , fulcrumed on shaft d^4 , in such a manner that lever h^5 , by means of its depending hook, which engages with the 70 studs upon the head of screw i^0 , turns the latter, and boss g' is moved across the space of one needle in the needle-bed, while lever h^6 impels screw i^{00} simultaneously, and which latter in turn reciprocates boss g^2 in a like manner. On bosses g' g^2 being reciprocated of course followers i' to i^4 are moved through connecting-bars s^3 to s^6 accordingly, either inward or outward. In the same manner as followers i' to i^4 are also point-carriers b^0 reciprocated 80 by screws i^0 i^{00} . In this case the movement of bosses g' g^2 is transmitted by arms a^5 , which extend between the down-projecting flanges a^6 and a^7 , Figs. 26^a and 28^a, to which bars s^7 and s^8 , connecting point-carriers b^0 , are fixed. 85 The process of narrowing can be seen from Figs. 14 to 20. The points b^0 take hold of the needles and pull them, supported by needle-actuating bars l' l^2 , so high that the loops slip below the latches of the needles, whereupon the motion of the points is reversed and the stitches are consequently transferred to the points, Figs. 14 and 16. Subsequently the points are raised and carry their stitches over one needle inwardly, while the feet of 95 those needles emptied by this operation are being plunged into the needle-bed by shoulders u' of followers i' to i^4 . In completing the narrowing operation the points transfer their loops upon the needles beneath them in the 100 well-known manner, returning afterward, together with needle-operating bars l' l^2 , in their original or idle position, Fig. 8. This operation is repeated as many times as narrowings are required for the fashioning of the leg of 105 the stocking, and for every narrowing a stud n has to be fixed on pattern-chain m , which consequently, in accordance with the number of studs, regulates the number of narrowings in the fabric at predetermined intervals. 110

After the narrowings of a stocking or after the leg portion of a sock have been made the working of the heel of the foot is commenced. The mechanisms devised for this purpose are 115 likewise actuated by pattern-chain m ; but before going into details respecting their construction or order of working it is necessary that the several and particular workings of cams x' to x^7 , Fig. 13, should be explained. 120 Cams x' to x^7 are mounted upon shaft e in close proximity to the pattern-chain device. Each cam consists of three disks $c' c^2 c^3$, Fig. 10^a, of which c' is fastened upon shaft e , c^2 being disposed loosely upon boss of c' , whereas c^3 is arranged laterally movable upon boss of c' and prevented from turning independently of disk c' by a spline fitting into a slot in the bore of disk c^3 . Disk c^3 is held in its normal position by a strong buffer-spring f^0 , Fig. 13, upon 125 shaft e , compressing c^3 constantly against c^2 . To render disk c^3 susceptible to be displaced, the opposite inner side faces of disks c^3 and c^2 are provided with wedge-shaped steps c^0 , 130

Fig. 10^a, which are placed in an inverse sense to one another in such a manner that they fit into each other and permit the disks to lie close side by side. Now if disk c^2 be arrested in its motion the wedges c^0 will force c^3 , compelled to continue in its rotation, in a lateral direction. For this purpose the rim of disk c^2 is provided with steps, and opposite each disk c^3 is arranged a spring-actuated plunger k' , Fig. 13, which slides in a grooved block with inwardly-projecting edges and which block is permanently fastened to the frame. Plunger k' , Fig. 10, is connected with lever p^5 , riding upon pattern-chain m , by lever l^4 . If, for instance, lever p^5 , Fig. 10, is raised by a stud n upon pattern-chain m , then plunger k' is pressed, by means of lever l^4 , toward disk c^2 , whereby the head of plunger k' , engaging with one of the steps in the rim of said disk, arrests it in its motion, with the effect that disk c^3 is displaced laterally upon shaft e , as described. In conjunction with disk c^3 is also displaced rod v^2 by disk c^3 bearing against lug g^0 , secured upon said rod, which latter carries also fork g^3 , embracing eccentric y^4 , Figs. 11 and 11^a, disposed laterally movable upon cam-shaft e . Eccentric y^4 on being moved in the direction of the arrow in Fig. 13 is brought to bear upon roller w^4 , which it reciprocates, together with the depending mechanisms. Said eccentric y^4 will remain in this position until lever p^5 has passed over stud n , by which it was raised, plunger k' has receded from disk c^2 , and disk c^3 has been pushed back by spring f^0 into its normal position, followed by rod v^2 , impelled by spring g^0 , Fig. 13. All motions are now transmitted from cam-shaft e . After every row of stitches formed cam x' , Fig. 13, consisting of three disks $c' c^2 c^3$, by displacing rod v' causes eccentric z' , Fig. 30^a, to bear upon roller w' of lever h^4 , which being fulcrumed upon shaft d^6 reciprocates followers $i^3 i^4$. This contrivance, as already explained, serves to throw out of action those of the needles which are emptied during the narrowing process with the aid of points, whereas now it is employed for rendering idle and active those needles which are destined to knit the bag-like heel (the so-called "Griswold" heel) by plunging and raising their feet. When set to work, said contrivance begins first by rendering idle the extreme working needle on the left, after the subsequent row of stitches the extreme working needle on the right, &c., constantly alternating one needle on the left with one on the right. It should be noted that the needles rendered inactive in this fashion keep their stitches until moved again into activity and that the hooks of said needles remain in line and on the same height as the working or active needles, as may be seen from Fig. 29^a. Followers $i^3 i^4$ are laterally displaced toward each other by bars $s^5 s^6$, Fig. 28^a, in conjunction with screws $i^0 i^{00}$, as described hereinbefore. Said screws are, while the narrowed part of the heel is being knitted, actuated by

levers $h^5 h^6$, Figs. 8 and 9. Rods $v^2 v^3$, &c., being displaced by cams $x^2 x^3$, &c., (each consisting of three disks c' to c^3), reciprocate eccentrics $z^2 z^3$, &c., in such a manner that they are brought to bear upon the depending arms of levers $h^5 h^6$, thus rocking them. All of the cams x' are alike, and each one in turn operates its respective rods v' , of which v' effects the right-hand outward movement of the sliding boss g' , while v^2 causes the return of same. v^3 moves the left-hand sliding boss outward, and v^4 again returns the same. v^5 and v^6 effect the sinking and raising of the jacks, and v^7 brings the pulling-off apparatus into action. The operation of knitting the heel is continued until the narrowed part of the heel has attained its desired length, whereupon the outthrown needles are alternately and in inverse order moved back into action, with the followers $i^3 i^4$ reversing their motion. For this purpose cams $x' x^2 x^3$ are thrown idle and cams $x^4 x^5 x^6$ substituted, with the effect that after every row of stitches formed lever h^{10} , firmly fastened upon shaft d^6 , is pushed in an upward direction by eccentric z^6 , the latter being actuated by rod v^6 in connection with cam x^6 , Fig. 30^a. With lever h^{10} are likewise reciprocated forks n^6 upon shaft d^6 and rod d^8 , coacting with followers $i^3 i^4$, whereby shoulders u^2 impinge against the tail projections of jacks a , and thereby bring them back again, together with their needles, in active position, Figs. 21 and 22. The followers $i^3 i^4$, as already hinted, have no longer an inward motion toward each other, but move outward away from one another. This motion is imparted by screw i^{00} being turned by pawl-supporting lever h^9 , which is reciprocated by eccentric z^5 , Fig. 9, acting together with cam x^5 and rod v^5 , Fig. 13, and by screw i^0 being actuated in the like manner by pawl-supporting lever h^8 , eccentric z^4 , Fig. 8, cam x^4 , and rod v^4 , Fig. 13. As soon as all the needles previously set idle have been brought back into work cams $x^4 x^5 x^6$ are thrown out of gear again, while steps $c c^0$, Fig. 8, are so regulated as to resume their original position. This means that the cams are thrown into the tube-knitting position and that the machine once more knits tubular plain fabric. It should be remarked that to pull off the bag-like fabric forming the heel a specially-constructed pulling-off apparatus is required, the nature of which can be apprised from my United States Patent No. 629,892. This pulling-off apparatus is actuated by cam x^7 , reciprocated by pattern-chain m .

As the fabric of a heel produced in the manner as described would show holes at those places where needles were thrown in and out of action, it has been devised to prevent the occurrence of such holes by closing them up with an additional loop. For this purpose the needles of the back needle-bed are provided with a second foot f^2 , Fig. 21. Immediately after such a needle has been thrown idle, as hereinbefore shown, it is alone and

independently, before the beginning of the next following row of stitches, thrown up again into receiving position, where yarn is delivered to it at the same time as to the 5 remaining active needles. The needles are brought singly into this receiving position by segments d^{10} and d^{11} alternately, Figs. 23 to 27. The segments d^{10} d^{11} are disposed on either side of the back needle-bed, mounted on horizontal spring-controlled pins e' e^2 , which rest in bearings fixed to rods t' and t^2 , respectively, these rods being attached to sliding bosses g' g^2 , governed by screws i^0 i^{00} . The pins bearing segments d^{10} d^{11} are provided on the opposite ends with eccentric projections m^7 m^8 , beveled inwardly, which serve to oscillate said segments. These eccentric projections, extending into the path of the cam-carriage, are reciprocated in the following manner: Triangle d^0 , being supported on cam-carriage b , makes, with the latter, the to-and-fro motion and depresses projections m^7 m^8 , thus forcing segments d^{10} d^{11} to turn upon their respective axes e' e^2 , whereby one needle is thrown into 20 receiving position, where yarn is supplied to it simultaneously with the working needles on the return stroke. As an additional loop is formed only upon that needle which during the production of the Griswold heel has 25 been set idle by plunging its foot, it is necessary that on every stroke of the machine only one needle should be raised. For this reason the eccentric projections m^7 m^8 have been beveled inwardly, with the effect that, on triangle d^0 sliding over the one or the other, segment d^{10} or d^{11} turns in opposite direction—viz., away from the needles, Fig. 23. The needle thrown up by segment d^{10} or d^{11} is immediately after receiving yarn moved back again 30 into idle position by triangle e^0 depressing its second foot f^2 , Fig. 28. Triangle e^0 works conjointly with the needle-reciprocating cams and is for this purpose fixed upon cam-carriage b by means of a suitably-adjusted support extending into the plane of the needles. 35 The travel of this device is, like that of the followers i^3 i^4 , regulated by screws i^0 i^{00} . As the formation of an additional mesh to prevent the occurrence of holes in the fabric is only 40 required when and where needles are thrown out of action in forming the heel by widening and narrowing, triangle d^0 is in work solely during the knitting of the heel and is for this purpose arranged in such a manner that it can 45 be thrown in and out of work, as desired. To this end a longitudinal bar z is devised, carrying wedges k^2 , Figs. 23, 25, 27, 29, and 30, which are adapted, on bar z being laterally displaced, to raise triangle d^0 into a recess in 50 the cam-carriage b , thus removing it out of the path of the eccentric projections m^7 m^8 , that are fixed on e' e^2 , respectively. The operation of this device is, like that of others in this machine, controlled and actuated by pattern-chain m , which to bring about this effect is provided with studs that are a little

higher than the ordinary ones, whereby lever p' , Fig. 13, regulating stops c c^0 , is lifted in such a manner that stop c^0 assumes position 3, Figs. 29 and 30, and bears against projection e^3 , and consequently displacing rod z in the direction of arrow 1, and triangle d^0 is brought into active position, as shown in Fig. 30. If, on the other hand, triangle d is to be rendered idle, then an ordinary stud is employed, which moves stop c^0 , by means of lever p' , in position 2, Figs. 29 and 30, in which position it bears against projection e^4 , pushing rod z in the direction of arrow 2, and thus moving triangle d^0 out of action. When now, 55 proceeding with the making of the foot, an instep is to be produced, as shown in Figs. 3, 5, 6, and 2, the requisite studs would bring the narrowing mechanism into action, which would operate in the manner as hereinbefore 60 described—viz., to overhang meshes to adjacent needles with the aid of points and render the empty needles idle by plunging their feet. The instep finished, the needle-operating cams continue in the tube-knitting 65 position and after the plain tubular part of the foot has been formed begins the shaping of the toe. The narrowing mechanism, together with the coacting follower device, is consequently thrown into action by means of 70 a stud or pattern-chain m , actuating the depending mechanisms. For every narrowing required in closing the toe of the foot stands a stud upon the pattern-chain m . Hitherto in closing the toe automatically and with the 75 aid of points the narrowing continued until the point-carriers b^0 , Fig. 7, on their laterally-opposed movement abutted against one another—viz., until the points correspond in number exactly with that of the stitches still 80 to be transferred. In order to close the point farther than this and to the last needle, the respective feet of sliding bosses g' g^2 , Figs. 26^a, 27^a, and 28^a, supporting the arms regulating the lateral travel of the follower device and the 85 point-carriers, which feet so far were made in one solid piece, are constructed in two parts independently movable and co-operating by means of screws i^0 i^{00} and a spring-actuated pawl-and-ratchet mechanism. It 90 acts in this way that the lower part b^0 , bearing arms a^4 , reciprocating followers i' to i^4 , moves uninterruptedly from needle to needle, whereas the upper portion, with arms a^5 , that control the motion of the point-carriers 95 b^0 , returns after performing one narrowing outward again over one needle impelled by screws i^0 i^{00} . For the subsequent narrowing it is moved inward again, whereupon it is retracted once more, and thus it continues until the toe has been closed to the last needle. 100 The construction can be seen from Fig. 27^a and is as follows: On the head of boss g' and below screw i^0 is pivoted a spring-depressed pawl g^6 , pointing with its prolonged 105 end toward the deflecting-stop f^3 , the top of which is tapered off, inclining in the path of

pawl g^6 . The base of boss g' is furnished with a ratchet v^0 , into the teeth of which fits spring-supported catch, that is pivotally connected with l^0 , the lower separate portion of 5 the foot of boss g' . The block l^0 , with rigid arms a^4 , is guided between bars and carries on one end a tooth-like projection z^0 , against which pawl g^6 impinges in the manner and for the purpose as hereinafter described. 10 Fig. 27^a represents the right-hand screw and follower device with screw i^0 . The left-hand device with screw i^{00} being identical is not shown. As soon as the web of the toe has been narrowed down to eight needles the 15 prolonged end of pawl g^6 will have slid upon the tapered surface of t^3 so high that projection Z^0 upon block l^0 has been liberated, with the effect that, the narrowing device being moved inwardly over one needle on either 20 side, said projection Z^0 glides away below pawl g^6 , and thus permits boss g' , on screw i^0 being retracted by lever h^8 , to be drawn outwardly without reciprocating block l^0 , which remains in exactly the position transported 25 to catch x , and ratchet V^0 being arranged in such manner that boss g' may move outwardly without impelling block l^0 as the teeth of ratchet v^0 , depressing pawl x , slide over it; but on being displaced inwardly pawl x registers firmly with one of the teeth of V^0 , and 30 consequently block l^0 is forced in the direction of boss g' . These operations are repeated until the web of the toe has been narrowed down to the breadth of two needles, when the 35 left-hand screw device, together with follower arrangement, is retracted, but not advanced again, and only the right-hand one is actuated in the manner as described, transferring the one loop to the last needle. Now, the fashioning of the toe being accomplished, the machine stops by itself, and it remains only for the stocking or sock to be taken out of the machine in the usual manner. 40

The stopping of the machine when required 45 is brought about automatically and is caused by pattern-chain m . For this purpose lever p^3 , Fig. 8, fulcrumed at d^{10} , is connected with pivoted lever b^5 by rod t^4 . Lever b^5 is provided at its free end with a projection M^0 , 50 against which presses a similar projection m^0 upon lever b^3 , securely fastened upon shaft w^2 , carrying likewise lever h^0 and its slotted continuation b^4 , that engages with rod s by means of pin s^{11} , as described. Spring f^8 , attached to lever b^3 , has the tendency of constantly keeping the latter in its normal position—i. e., the position it assumes on the machine having been stopped. To throw the machine out of gear, a stud upon pattern-chain m raises lever p^3 , which, by means of rod t^4 , depresses lever b^5 , so that projection m^0 liberates lever b^3 , which, being impelled by spring f^8 , causes rod s to rise, whereupon rod s' enters recess j^0 and cone o recedes from 65 its cavity in fly-wheel pulley r^8 , thus stopping the machine, as hereinbefore set forth.

In proportion as the breadth of the web is diminished during the formation of the toe the weight pulling off the fabric has to be reduced also. To this end an automatic weight-relieving tackle at the left end of the machine has been arranged, as shown, consisting of three vertical rods held in one stand, two of which serve as guides for the pulling-off weights, while on the third one at certain intervals several brackets c^4 are fixed, which arrest the weights on their downward way. To render the discharging of such weights automatic during working process of the machine, the distance s^0 between the arms of the different brackets c^4 is differentiated in such a manner that it decreases in every bracket downward. The weights k^3 to k^5 , suspended on a chain passing over a roller at the top end of the vertical rods, are of various lengths in conformity with the distances s^0 between the arms of brackets c^4 . The weights in descending are arrested one after the other, the longest first and by degrees the shorter ones, without requiring any manipulation by hand, and in this manner the strain of weight on the fabric is reduced as its breadth is diminished. 75

During the action of pulling-off apparatus, as per specification of my United States Patent No. 629,892, and while the heel is being made the action of weights k^3 to k^5 , Fig. 30^a, must be arrested. To do this automatically without interrupting the run of the machine, a stud upon pattern-chain m will actuate a certain mechanism and cause roller r^{11} , which stands under the influence of weights k^3 to k^5 , to be arrested. For this purpose, as shown in Figs. 12, 12^a, 12^b, and 12^c, cam-shaft e carries laterally movable a disk and eccentrically fixed to it a cam y^7 . On the disk being displaced by eccentric x^7 , moving rod v^7 in the manner as hereinbefore described with regard to x' , &c., spring-actuated roller w^3 of lever f^4 , Fig. 30^a, is pressed against the side of the disk until the face of eccentric y^7 reaches the level of the face of the disk at j^{00} , when roller w^3 is forced and kept onto it by spring f^5 . Lever f^4 is no longer rocked by cam y^7 . Pawl h^6 engages with ratchet-wheel r^0 , fixed upon the same shaft d^{13} as roller r^{11} , completely arresting the latter, and consequently also the action of weights k^3 to k^5 . Roller r^{11} is in due time automatically released again by the disk of y^7 being shoved back into its normal position, and roller w^3 is once more being reciprocated by y^7 . 110 115 120

So as to save the lifting by hand into active position by the sliding frame of the pulling-off apparatus, as per specification of my United States Patent No. 629,892, a ratchet-bar m^9 , Fig. 9, suitably arranged beneath each frame at the back of the machine, has been provided, which bar is raised step by step by means of pawl e^5 engaging with the teeth of that bar and by moving lever d^{14} up and down by hand. The bar m^9 is prevented from dropping, on pawl 125 130

e^5 receding for another lift, by wiper e^6 upon shaft d^{15} engaging with one of the teeth of bar m^9 , thus maintaining it in its position.

Having thus fully described the nature of 5 this invention, what I desire to secure by Letters Patent of the United States is—

1. In a Lamb knitting - machine having an apparatus for automatically overhanging meshes by points, the combination of a needle-bed B consisting of a solid plate n^2 having transverse grooves, separate plates n^4 mounted in said grooves and forming guides for the needles and jacks, with a longitudinal recess traversing the solid plate, jacks having claw-shaped basal projections adapted to enter the recess when lowered, for the purpose and substantially as described. 15

2. In a Lamb knitting - machine having an apparatus for automatically overhanging meshes by points, the combination of a needle-bed B, consisting of a solid plate n^2 having transverse grooves, separate plates n^4 mounted in said grooves and forming guides for the needles, and jacks with cross-plates n^{20} provided with teeth, said cross-plates being mounted upon the transverse plates n^4 , the teeth taking into the intermediate spaces between the different transverse plates n^4 for the purpose and substantially as described. 20

3. In a Lamb knitting - machine, having an apparatus for automatically overhanging meshes by points, the combination of a needle-bed B consisting of a solid plate n^2 , having transverse grooves, separate plates n^4 mounted in said grooves and forming guides for the needles and jacks appertaining thereto with a longitudinal recess traversing the solid plate, jacks a having a claw-shaped basal projection n' and entering said longitudinal recess when plunged, for the purpose and substantially as described. 30

4. In a Lamb knitting - machine, having an apparatus for automatically overhanging meshes by points, the combination of a needle-bed B consisting of a solid plate n^2 , having transverse grooves, separate plates n^4 mounted in said grooves and forming guides for the needles and the jacks appertaining thereto, with a longitudinal recess traversing the said 40 plate, a jack a having a claw-shaped basal projection n^0 entering said longitudinal recess when plunged, a follower arranged on both sides of each needle-bed, a cam-shaft e suitably brought into connection with and actuating the follower, said follower moving the jacks a to effect the automatic rendering active or inactive of certain working needles simultaneously with the sinking of emptied needles into the needle-bed, substantially 50 and for the purpose as described. 55

5. In a Lamb knitting - machine having an apparatus for automatically overhanging meshes by points, the combination of followers, needle-shifters i' arranged within said 60 followers and effecting the raising and sinking of the jacks, points for overhanging

meshes, a feed-screw i^0 , a support g' mounted upon said screw i^0 , arms a^5 fixed to the support and displacing the points laterally, a second support l^0 having arms a^4 causing the lateral movement of the followers and consequently of the needle-shifters i' , means for coupling both supports for narrowing and widening purposes, substantially and for the purpose as described. 70

6. In a Lamb knitting - machine having an apparatus for automatically overhanging meshes by points, the combination of a shaft e rotating constantly and carrying movable cams, a second cam-shaft i independent of the first and carrying fixed cams, followers moving the jacks, means for connecting the shaft e to the follower for influencing the same during the process of engaging and disengaging working needles for producing the heel, the second shaft i influencing the same followers during the automatic narrowing by points, substantially and for the purpose as described. 80

7. In a Lamb knitting - machine having an apparatus for automatically overhanging meshes by points, the combination with two shafts e and i carrying eccentric cams, one of the shafts e rotating constantly and having its cams movable, the other i rotating during the narrowing process and having its cams fixed upon it, oscillating shafts $d^6 d^7$ arranged on each side of the machine alternatively operated by the shaft e or by the shaft i means for rotating said shaft i only during the narrowing by points, for the purpose and substantially as described. 90

8. In a Lamb knitting - machine having an apparatus for automatically overhanging meshes by points, the combination of a rotating shaft e carrying eccentric cams movably mounted thereon with a second shaft i carrying fixed eccentric cams and actuated during the narrowing by points, shafts $d^6 d^7$ arranged on both sides of the machine and alternatively operated from both shafts e and i , levers $h^8 h^4 h^{10}$ influenced by the cams of the shafts e , i , and oscillating the shafts $d^6 d^7$, followers arranged at both sides of the needle-bed, needle-shifters i' influencing the jacks and being arranged within said followers, means for transmitting the oscillations of the shafts $d^6 d^7$ to the needle-shifters, substantially and for the purpose as described. 105

9. In a Lamb knitting - machine having an apparatus for automatically overhanging meshes by points, the combination of a support g' effecting the lateral displacement of the points with a second support l^0 coupled to the first for narrowing and widening purposes and means for uncoupling said supports thereby reversing the approaching movement of the points for closing up the toe, substantially and for the purpose as described. 115

10. In a Lamb knitting-machine a needle-bed B, needles having two feet, an upper f^2 120

and a lower one f , the needles with their lower feet f being adapted to be plunged into the needle-bed, cams l effecting the knitting of ordinary ware by working with the lower feet f of the needles, jacks a plunging the lower feet f of the needles during their disengagement, followers actuating said jacks a , and means for pushing upward plunged needles by moving them at their upper foot f^2 for the

purpose of allowing additional loops to be ¹⁰ formed around the last mesh holding plunged needles, substantially as described.

In witness whereof I have hereunto set my hand in presence of two witnesses.

HERMANN DONNER.

Witnesses:

EUGEN WOHL,

GEORG LIEBESKIND.
